(57) **CLAIM**

The ornamental design for a insulated box assembly, as shown and described.

DESCRIPTION

FIG. 1 is a top perspective view of an insulated box assembly, showing our new design;

FIG. 2 is a bottom perspective view thereof;

FIG. 3 is a rear elevation view thereof;

FIG. 4 is a front elevation view thereof;

FIG. 5 is a right-side elevation view thereof;

FIG. 6 is a left-side elevation view thereof;

FIG. 7 is a top view thereof; and,

FIG. 8 is a bottom view thereof.

The broken lines in the drawing figures illustrate portions of the insulated box assembly which form no part of the claimed design.

1 Claim, 6 Drawing Sheets
